UNITED STATES PATENT OFFICE

1,945,396

GRINDING MACHINE

Carl H. Gerling, Schenectady, N. Y., assignor to
 General Electric Company, a corporation of
 New York

Application April 19, 1929. Serial No. 356,537

2 Claims. (Cl. 51—166)

The present invention relates to improved apparatus or machines for grinding or surfacing hard metals and particularly metal compositions which consist largely of a hard metal carbide, such as tungsten-carbide, but contain an appreciable amount of a binder or cementing metal such as cobalt. A composition of this character is described in the patent to Schröter No. 1,549,615. Such compositions have a hardness approaching that of the diamond and at the present time are employed to a large extent as metal cutting tools, the composition employed being usually in the form of a tool bit which may be welded or brazed to a steel shank.

15 Heretofore great difficulty has been encountered in grinding such tool bits. For example, when ordinary automatic surface grinding machines are employed the ground surfaces of the tool bit are so uneven that when brazed or welded 20 to a shank the tip does not lie exactly flat and therefore frequently cracks off in the operation of the tool. It is also difficult to obtain a sharp, even edge on the tool when the ground surfaces are uneven. Moreover, the tool edge is readily 25 chipped off when the ordinary rigid grinder is employed. These difficulties have necessitated the use, to a large extent, of hand grinders in surfacing such tool bits. When hand grinders are employed however, the grinding process is not 30 only very slow but expert workmen are required, since a tool bit may easily be destroyed in the grinding operation. Moreover, it is practically impossible to form accurate angles between adjacent surfaces of a tool bit with a hand grinding 35 machine.

It is one of the objects of the present invention to provide an improved grinding machine which may be operated by unskilled labor and which is capable of grinding at relatively high speed a perfectly flat surface on hard metals and particularly 40 on cemented tungsten-carbide tool bits.

In carrying out my invention, I provide means whereby, in the usual automatic grinding machine, the grinding wheel may be held in its operative position by resilient means but is capable 45 of a slight limited movement, for example about $\frac{1}{2}$ ", away from the work. A machine of this character permits the employment of unskilled labor in grinding the tool bits and produces 50 ground surfaces which are exactly flat and which may be ground at any exact angle with respect to one another.

The novel features which I believe to be characteristic of my invention are set forth with particularity in the appended claims. The inven- 55

tion itself however will best be understood from reference to the following specification when considered in connection with the accompanying drawing in which Fig. 1 represents a view partly in elevation and partly in section of an automatic 60 surface grinding machine which embodies the features of the present invention, while Fig. 2 is a view partly in section and partly in elevation of a cutter grinder which also embodies features of the present invention.

Referring more particularly to the drawing, I have indicated at 1 in Fig. 1 the framework of an ordinary automatic surface grinding machine provided with a reciprocating table 2 adapted to be driven in opposite directions by an electric 70 motor 3 connected to reversing gearing 4 through a counter-shaft 5 provided with pulleys 6 and 7. Motor 3 also drives a small pulley 8 which is attached to the surface grinding wheel 9 through pulleys 6 and 10. Grinding wheel 9 and the attached pulley 8 are provided with bearings in a block 11 which is slidable vertically on guideways 12 and secured to the lower end of a worm shaft 13 which extends upwardly through an opening 14 in the frame 1. The driving system 75 and structure thus far described is old and forms no part of the present invention.

A casting consisting of a bevel gear 15, a cylindrical extension 16 and an enlarged cup-shaped portion 17 is rotatably mounted in the opening 80 14. The casting is provided with a threaded portion 18 which engages somewhat loosely the threads on the worm shaft 13 so that the worm may move a short distance longitudinally, for example about $\frac{1}{2}$ ", independently of the casting. 90 A substantially flat plate 19 is loosely mounted at the lower end or opening in the cup-shaped member 17 and is provided with a plurality of projecting pins 20 which fit loosely in cooperating slots 21 in the cup-shaped member 17. These pins are 95 provided with enlarged head portions 22. A coiled spring 23 surrounds the worm shaft 13 and bears against the bottom of the cup-shaped member 17 and the plate 19 thus urging the worm shaft and grinding wheel downwardly as far as possible in 100 any one adjusted position of the grinding wheel. The tension of spring 23 may be adjusted by removing pins 20 and turning the plate 19 on shaft 13.

A relatively small bevel gear 24 engages the 105 bevel gear 15 and may be operated by means of a hand wheel 25 to provide longitudinal adjustment of the grinding wheel. When the bevel gear 24 is rotated in either direction, the cup-shaped member 17 and the plate 19 are also ro- 110

tated and the worm shaft 13 moved either upwardly or downwardly. Spring 23 holds the grinding wheel at the lowest point in any adjusted position. Owing to the loose fit between the worm shaft 13 and the threaded portion 18 of the casting the grinding wheel may be moved upwardly a small amount independently of the casting. In grinding certain materials such as an alloy of tungsten-carbide and cobalt, this movement usually will be quite small. A margin of about $\frac{1}{2}$ " is usually allowed. This margin however may obviously be greater or smaller if desired.

With a grinding machine of the type described, it is possible to quickly grind very hard metals of the character described in the above mentioned Schröter patent so that they will be absolutely flat. For example, if one ground tool bit is rubbed across the surface of a second ground tool bit so as to exclude any air film from between them it will be found that the surfaces are so flat that very often the lower tool bit will stick to the upper tool bit when the latter is lifted. Moreover, with my improved grinder the edges of the tool bit are not chipped and the wear on the grinding wheel is far less than is the case in the ordinary grinding machine.

In Fig. 2, I have illustrated my invention in connection with a cutter grinder. In this figure a pedestal 26, usually employed with such grinders, is provided at its upper end with an integral U-shaped bracket 27 which carries bearings 28 and 29 for a shaft 30 driven by step pulleys 31 and 32. Shaft 30 is provided at the outer end thereof with a grinding wheel 33. The opposite end of the shaft is provided with an enlarged head portion 34. Two plates 35 are loosely mounted on shaft 30 and held against an interposed ball race 36. A spring 37 presses against the outer plate 35 and urges shaft 30 and grinding wheel 33 in an outward direction toward the work to be ground. The force applied to shaft 30 by the spring 37 may be adjusted by manipulation of a screw plug 38 mounted in a cap 39 which is secured to the supporting member 29' for bearing 29.

Spring 37 normally urges the step pulleys 31 and 32 against a ball race 40 confined between plates 41 loosely mounted on shaft 30. Shaft 30, however, may move inwardly and away from the work a small distance which usually will not exceed $\frac{1}{2}$ ", the amount of inward movement being limited by a nut 42 secured to the end of bearing 29, as clearly indicated in Fig. 2.

Although I have illustrated my invention in connection with surface and cutter grinders, it is clear that the invention is not limited to those machines only but may be applied to various types of grinding machines.

What I claim as new and desire to secure by Letters Patent of the United States, is:

1. In a grinding machine, a grinding wheel, means including a worm shaft for adjusting the position of said wheel, a nut loosely engaging said shaft and held against longitudinal movement to thereby permit a limited movement of the wheel away from the work in any adjusted position of said wheel and resilient means interposed between said nut and shaft to yieldingly hold said wheel in contact with the work.

2. In an automatic surface grinding machine, a grinding wheel, means for adjusting the position of the wheel, said means including a worm shaft, a member loosely and rotatably mounted on said shaft but held against longitudinal movement, said member being provided with screw threads loosely engaging the threads on the worm shaft, a second member mounted on said worm shaft and provided with a threaded portion engaging said worm shaft, said second member being connected to said first member to rotate therewith but to move in a longitudinal direction independent thereof, and resilient means interposed between said members to urge said grinding wheel against the work and to permit movement of the wheel away from the work, the screw threads on said first member limiting the movement of the grinding wheel away from the work in any position to which it may be adjusted.
